UNITED STATES PATENT OFFICE.

AUGUST CLAAS, OF HARSEWINKEL, GERMANY.

KNOTTER FOR BINDING MOWERS AND STRAW BINDERS.

Application filed September 15, 1924, Serial No. 737,802, and in Germany September 20, 1923.

The hitherto known knotters for binding-mowers and straw-binders comprise a stationary base member and a movable tongue engaging with its front end in said base member. Said knotters have the drawback that they are adapted for knotting binding cords of a positive thickness only. With a too thick cord, the tongue does not liberate the knot as it is too firmly pressed against the base member by the binding; and with a too thin cord, the tongue is not capable of holding the binding-cord as the latter slips through base member and tongue.

Said drawbacks are overcome by the subject matter of the present invention, in which binding-cords of different thicknesses can be employed. According to the invention, the improved knotter comprises a stationary base member, an upper member with limited movement with reference to the base member, and a tongue which is guided between base and upper members so as to be easily turnable corresponding to the actual thickness of the binding cord; the operation of the upper member being effected in dependence upon the movement of the tongue but so that the latter maintains always a free play with reference to the upper member.

The accompanying drawing shows in Figs. 1 and 2 sectional side views at right angles to one another of the improved device.

The device comprises a stationary base member *a* integral with the knotter foot *b*, while an upper member *c* is pivotally arranged at *e* in the cup *d* of the knotter of which said base member forms the bottom part. The downward movement of said upper member *c* is limited by an abutment *f* bearing against the top edge of the base member *a*. Within the upper member *c* a tongue *g* is located and also pivoted at *e* and adapted to engage with its hooked front end *i* in a recess *h* of the base member *a*, while it can be operated by hand with the aid of an implement (rod or the like) inserted in its hollow upwardly directed rear end. Said tongue has in the upper member *c*, when the latter bears with its abutment *f* against the top edge of the base member *a*, still a free play

of movement in downward direction, so that the hook *i* can engage more or less deeply in the recess *h*, whereby also with a thick binding-cord the slipping of the knot and the knotting itself are ensured.

By the binding mechanism the binding-cord is wound around the sheaf and laid around the upper and base members of the knotter, which then ties the knot, this being already known in the art. However, the opening of the tongue *g* results in a simultaneous opening of the upper member *c*. Upon the binding-cord being passed between base member *a* and tongue *g*, the latter is, for clamping the cord, again closed, the upper member *c* being closed simultaneously until its abutment *f* strikes upon the base member *a*, whereas the tongue *g* has still a free play of movement by its front hook *i* engaging in the recess *h* of the base member *a*, whereby it clamps the binding-cord, whether thin or thick, so that in any case the finished knot must slip off.

What I claim, is:—

In a knotter for binding-mowers and straw-binders, the combination with the knotter foot, of a cup at the lower end of the latter, a stationary base member having a recessed front end and integral with said knotter foot and forming the bottom part of said cup, an upper member pivotally mounted in said cup, an abutment on said upper member limiting the downward movement thereof, a hand-operated tongue pivotally mounted within and on the same pivot as said upper member and adapted to be opened together with the latter but having still a free play of movement in downward direction when said upper member is stopped in its downward movement by said abutment, and a hook at the front end of said tongue adapted to engage more or less deeply in the recessed front end of said base member during the downward movement of said tongue.

In testimony wherof I have hereunto set my hand.

AUGUST CLAAS.
